UNITED STATES PATENT OFFICE.

GEORGE F. ROSE, OF HYNDSVILLE, NEW YORK.

FILM-SPACING DEVICE FOR CAMERAS.

Application filed May 11, 1923. Serial No. 638,252.

- The present invention relates to film feeding mechanism for cameras of a generally similar nature to that disclosed in my application relating to "equal spacing device for film cameras," Ser. No. 339,723, abandoned April 22, 1925, and consists in the combinations and arrangements of elements hereinafter described and particularly set forth in the accompanying claims.
- 10 The purpose of the invention is to provide a film feeding mechanism wherein the winding or positively actuated reel will be automatically controlled to move at amounts commensurate with the increasing diameter 15 of the winding film to the end that there will be equal and uniform spacing of the film for exposure.

A further purpose of the invention is to provide a device of simple construction 20 capable of effectively accomplishing these results in an easy and simply performed manner, and the mechanism of which will not require any alteration in the camera structure for its application.

25 The invention is disclosed by way of illustration in the accompanying drawings, wherein:—

Fig. 1 is a side elevational view of a portion of a camera showing the application 30 of the device; and

Fig. 2 is a transverse sectional view thereof taken in line with the shaft of the winding roll.

Referring to the construction in further 35 detail, 3 indicates the frame or casing of the camera within which are suitably journaled the winding reel 4 and unwinding reel 5 of the film 6 which traverses the usual idler rollers 7; 8 represents the shutter mounted 40 on the rollers 9, and 10 is the usual curtain mounted on the pair of rollers 11. These parts are of the usual or otherwise suitable construction and no claim thereto is made in this case.

45 The winding reel 4 is adapted to be intermittently operated from a continuously operating shaft 12 through a gearing train consisting of a pinion 13 on the shaft 12 that meshes with a larger pinion 14, and 50 said pinion 14 in turn meshes with the pinion 15 that is loosely journaled on the shaft 16 of the winding reel 4 as shown. The gear wheel 15 is adapted to be constantly driven from the prime mover 12 and intermittently 55 operates the winding reel 4 through the novel form of translating mechanism con-

stituting the subject-matter of this invention.

The translating device per se consists of an actuator 17 loosely journaled on the shaft 60 16 and carrying a spring tensioned pawl 18 that coacts with the ratchet wheel 19 keyed to the shaft of the winding reel 4. Said actuator is moved to operate in a clockwise direction through a stud or other projection 20 on the wheel 15 that engages with the abutment 21 at the end of the lever 22 and which lever is pivotally mounted at 23 on the actuator arm 17.

The lever 22 is normally held under the 70 tension of spring 24 to position the stop 21 in the path of movement of stud 20, and by the engagement of said stud and abutment (20 and 21) the actuator 17 is moved in a 75 clockwise direction and thereby transmits a like motion to the winding reel 4 through the pawl and ratchet engagement.

The extent or angular degree of movement of the actuator 17 is automatically controlled to be commensurate with the constantly increasing diameter of the winding film for the purpose of effecting equal and uniform spacing of the film for exposure. To accomplish this, a presser arm 25 is mounted fast 80 on a rock shaft 26 and carries a roller 27 85 that has constant engagement with the film as the latter is wound upon the reel 4, and through such engagement the said arm 25 is moved on its pivot and effects a like movement of the trip arm 28, also mounted fast 90 on the said shaft 26 and fixed to operate with the member 25.

The trip arm 28 carries a roller 29 that is adapted to contact with the cam 30 carried by the lever 22, and through such engagement said lever is tripped to disengage the parts 20 and 21 and thereby free the actuator 17 to be retracted under the tension of the spring 31 coiled around shaft 16 having one end anchored to the casing 3, and the other end fastened to arm 17. An abutment or stop 32 mounted on the casing limits the return stroke of the actuator, and it is therefore from this position that the operating stroke of the actuator begins for 100 moving the winding reel.

As gear 15 rotates, shoulder or pin 20 contacts with shoulder 21, and in the further rotation of gear 15 the lever 22 and arm 17 are carried around the shaft 16 causing the pawl 18 to turn the ratchet wheel 19 which rotates shaft 16 and the winding reel 4 for the pur-

pose described. At some point in such movement of the lever 22 the cam 30 contacts with the roller 29 and as the latter cannot move out of the way the cam 30 is pressed 5 downwardly causing shoulder 21 to slip out from under shoulder or pin 20. There upon the lever 22 and arm 17 are quickly retracted by the spring 31 until lever 22 comes to rest against stop 32. As more film is wound 10 upon the reel 4 roller 27 moves away from shaft 16 and roller 29 moves toward shaft 16 and therefore the roller 29 will act proportionately earlier on the member 30 to trip the shoulder 21 and permit the parts 22 and 15 17 to return to their position of rest against stop 32, the shape of the cam 30 is that of a spiral with its center in the middle of shaft 16. In other words, as the diameter of the reel increases with the winding of 20 the film, the radius of curvature of the cam decreases.

It will therefore be seen from the foregoing that the winding reel 4 will be given an intermittent rotary motion through the 25 actuator and that the degree or extent of each movement will be automatically controlled by the constantly increasing diameter of the reel as it is wound for the purpose stated.

As the film is wound around the reel 4, and the diameter of the reeled film increases thereon, roller 29 is moved inwardly and acts further along the path of the cam 30 on a smaller radius. This causes a progressively earlier tripping of the lever 22 and the degree of rotation of the reel 4 is progressively decreased, so that the same amount of film is drawn off the supply reel 5 in each cycle of operation. Prior to the 40 first cycle of operation reel 4 is practically empty and a substantially full revolution of said reel is needed to draw the proper length of film from reel 5 for an exposure. In other words, with the reel empty the arm 17 45 will turn through almost a complete revolution before the roller 27 drives apart cam 30 to trip the lever 22. Fig. 1 shows the relation existing between roller 29 and part 30 prior to the first cycle of operation when 50 said part 30 must pass by roller 29.

It is obvious that those skilled in the art may vary the details of construction and arrangement of parts without departing from the spirit of my invention, and therefore I do not wish to be limited to such features except as may be required by the 55 claims.

What is claimed is:

1. In a winding apparatus, the combination of a reel, an actuator for moving the reel, a lever carried by said actuator, a power driven element for engaging said lever to move the actuator, and means automatically controlled by the material wound 60 upon the reel to release said lever from en-

gagement with the power element in such manner as to regulate the operating movement of the actuator, substantially as set forth.

2. In a winding apparatus, the combination of a reel, an actuator operable to move the reel, a lever carried by said actuator, a power driven element for engaging said lever to move the actuator, an arm adapted to contact with the material wound on the 70 reel, and a trip member carried by said arm adapted to engage with and release the actuator lever from the power element whereby to regulate the operating movement of the actuator, substantially as set forth. 75

3. In a winding apparatus, the combination of a reel, an actuator operable to move the reel, a lever carried by said actuator and provided with an abutment, a power driven element adapted to engage said lever abutment and impart movement to the actuator for moving the reel, a presser arm adapted to contact with the material wound on the reel, and a trip arm connected to said presser arm adapted to engage with said lever and release the same from the power driven element whereby to regulate the operating movement of the actuator, substantially as set forth. 80

4. In a winding apparatus, the combination of a reel, an actuator operable to move the reel, a lever carried by said actuator and providing an abutment, a power driven element having a member adapted to engage the lever abutment and thereby impart movement to the actuator for moving the reel, a cam mounted on said lever, a presser arm adapted to contact with the material wound on the reel, and a trip arm actuated by said presser arm adapted to engage with said cam to release said lever from engagement with the power element whereby to regulate the operating movement of the actuator, substantially as set forth. 90

5. In a winding apparatus, the combination of a reel provided with a ratchet, an actuator arm mounted concentric with the reel, a pawl on the actuator operable with said ratchet to turn the reel, a retraction spring for the actuator, a lever carried by the actuator and providing an abutment, a power driven element having a member adapted to engage said lever abutment and impart movement to the actuator for moving the reel, a presser arm adapted to contact with the material wound on the reel, and a trip arm movable by said presser arm to engage with and release said lever from engagement with the power element whereby to regulate the operating movement of the actuator, substantially as set forth. 100

6. In a winding apparatus, the combination of a reel having a ratchet, an actuator mounted concentric with said ratchet, a pawl carried by said lever cooperable with 105 110 115 120 125 130

- said ratchet to move the reel, a retraction spring for the actuator, a lever pivotally mounted on the actuator and provided with an abutment, a power driven element having 5 a member adapted to engage said lever and abutment and impart movement to the actuator for moving the reel, a cam carried by said lever, a presser arm adapted to contact with the material wound on the reel, 10 and a trip arm connected to said presser arm operable to engage said cam and release said lever from the power driven element whereby to regulate the operating movement of the actuator.
- 15 7. In a film feeding apparatus for cameras, the combination of a reel having a ratchet, an actuator mounted concentric with said ratchet, a pawl mounted on the

actuator cooperable with the ratchet to move the reel, a retraction spring for the actuator, a lever pivotally mounted on the actuator and provided with an abutment, a power driven element having a member 20 adapted to engage said lever abutment and impart movement to the actuator for moving the reel, a cam mounted on said lever, a pivotally mounted presser arm adapted to contact with the film wound on the reel, and a trip arm connected to said presser arm 25 adapted to engage said cam and release said lever from engagement with the power element whereby to regulate the operating stroke of the actuator, substantially as set forth.

In testimony whereof I affix my signature.
GEORGE F. ROSE.
